UNITED STATES PATENT OFFICE.

GEORGE HERZBERGER, OF TRENTON, NEW JERSEY.

ATTACHMENT FOR GAS-STOVES.

1,181,138.

Specification of Letters Patent.

Patented May 2, 1916.

Application filed May 25, 1915. Serial No. 30,353.

To all whom it may concern:

Be it known that I, GEORGE HERZBERGER, subject of the Emperor of Germany, residing at Trenton, in the county of Mercer and State of New Jersey, have invented new and useful Improvements in Attachments for Gas-Stoves, of which the following is a specification.

This invention relates to improvements in attachments for gaseous fuel burning stoves and has particular application to a heat conserving device.

In carrying out the present invention, it is my purpose to provide a heat conserving device for gaseous fuel burning stoves whereby the heat from the burner will be concentrated around the burner and delivered to the utensils supported above the burner, and then delivered to a heat retaining element disposed below a second utensil, and adapted to heat such second utensil by the heat received from the burner.

It is also my purpose to provide a device of the class described which will embrace the desired features of simplicity, efficiency and durability, which may be manufactured and marketed at small cost and which may be readily applied to a gaseous fuel burning stove.

With the above and other objects in view, the invention consists in the construction, combination and arrangement of parts hereinafter set forth in and falling within the scope of the claim.

In the accompanying drawings, Figure 1 is a top plan view of a heat conserving device constructed in accordance with the present invention. Fig. 2 is a longitudinal sectional view therethrough showing the same applied to a stove. Fig. 3 is a bottom plan view of the device. Fig. 4 is a sectional view on the line 4—4 of Fig. 2. Fig. 5 is a similar view on the line 5—5 of Fig. 2.

Referring now to the drawings in detail, 45 1 designates a plate formed with an opening 2 adjacent to one end thereof and a relatively small opening 3 adjacent to the other end thereof. Depending from the bottom of the plate 1 and surrounding the 50 openings 2 and 3 and extending longitudinally of the plate is a flange 4 having the central portions thereof between the openings 2 and 3 disposed in close proximity to each other and coöperating with that 55 portion of the plate between the openings to form a passage that connects the open-

ings. The upper surface of the plate 1 concentrically of the openings 2 and 3 is rabbed as at 5, 5 to form seats, and secured to the lower edge of the flange 4 and preferably of a configuration corresponding to that of the flange is a plate 6 serving to close the lower end of the space formed by the flange. In the present instance, the plate 6 embodies a stationary section 7 and a 60 movable section 8 and the movable section 8 is disposed below the opening 2 and has one end edge thereof hinged as at 9 to the end portion of the flange 4, and the remaining end edge adapted to abut the adjacent 65 end of the stationary section 7 of the plate. A lug 10 is pivoted to the under surface of the stationary section 7 of the plate and is adapted to engage the adjacent portion of the movable section 8 to hold the latter 70 in closed position. The movable section 8 of the plate is formed with segmental slots 9', 9' placed end to end and arranged concentrically of the axis of the opening 2 and disposed within the slots and suitably secured therein are foraminous strips 10.

Disposed within the end of the flange 4 below the opening 3 and suitably secured therein is a heat retaining element 11 in the form of a soapstone or the like and preferably circular in formation and having the upper surface convexed as at 12 and the lower surface concaved as at 13. This soapstone is formed with vertical passages 14 to facilitate the circulation of air through 90 the stone so that such air may be heated when the stone is in a like condition. Suitably secured to the stationary section 7 of the bottom plate 6 below the heat retaining element 11 is an auxiliary burner 15.

In practice, the plate 1 is placed upon the stove and the end of the flange 4 surrounding the opening 2 incloses the main burner of the stove, as clearly illustrated in Figs. 2 and 4. The auxiliary burner 15 is connected up with the supply pipe of the main burner by means of a pipe 16 and located in the pipe 16 is a cut off cock 17 equipped with an upwardly projecting handle 18 extending through the plate 1. Secured to the upper end of the handle 18 is a radially projecting finger 19 movable over a segmental plate 20 fastened to the upper surface of the plate 1 and having the words "Open" and "Closed" inscribed thereon adjacent to the 105 opposite ends of the plate, respectively. The utensils to be heated are placed upon

the plate over the openings 2 and 3 and are supported by the seats 5, 5, thereby closing the openings 2 and 3 to prevent the escape of heat around the utensils or receptacles. 5 The main burner below the opening 2 is now lighted and the heat therefrom is concentrated around the bottom of the pan by the adjacent portion of the flange 4 and passes through the passage formed by the central 10 portions of the flange and the corresponding portions of the plates 1 and 6 and heats the soapstone heating element 12. As the element 12 is heated, the air circulating through the passages 14 impinges against 15 the bottom of the receptacle over the opening 3, thereby heating the contents of such receptacle. The end of the flange 4 adjacent to the opening 3 is formed with an outlet aperture 21 designed to promote combustion. When it is desired to feed air to the main burner below the opening 2, the movable section 8 of the plate 6 is swung to open position, while when it is desired to decrease the amount of air fed to the burner 20 25 the plate is closed, and the burner supplied with a small quantity of air by means of the foraminous strips 10 in the openings 9 of the movable section. Should it be desired to heat the element 12 rapidly, the burner 15 30 35 is supplied with fuel and lighted and after the element 12 has been heated to the desired temperature, the auxiliary burner 15 is extinguished and the heating element supplied with heat from the main burner. Fastened to the bottom plate 6 within the heat conducting passage is an inclined deflecting plate 22 whereby the heat from the main burner is deflected through the passage and against the heating element 12. The mar-

ginal edges of the plate 1 are preferably 40 downturned as at 23 and are designed to rest upon the adjacent portions of the stove to support the device in proper position.

While I have herein shown and described one preferred form of my invention by way 45 of illustration, I wish it to be understood that I do not limit or confine myself to the precise details of construction herein described and delineated, as modification and variation may be made within the scope of 50 the claim without departing from the spirit of the invention.

I claim:

A heat conserving device for gas stoves comprising a plate having openings formed 55 therein spaced apart, a flange depending from the bottom of said plate and surrounding the openings and acting to form a passage connecting the openings, said flange having one end portion adapted to encircle the burner of the gas stove below one of said openings, a heat retaining element in the remaining opening adapted to receive heat from the burner through the passage formed by said flange and having vertical 60 65 passages formed therein and the lower surface concaved, an auxiliary burner below said heat retaining element and a bottom plate secured to the lower edge of said flange and comprising a stationary section and a 70 movable section.

In testimony whereof I affix my signature in presence of two witnesses:

GEORGE HERZBERGER.

Witnesses:

LYMAN FILLMAN,

EDWARD C. SKELMAN.
